DESIGN FOR A CONTAINER CAP OR THE LIKE

Robert G. Peck, Jr., Chicago, Ill., assignor to The Aridor Company, Chicago, Ill., a corporation of Illinois

Application July 25, 1935, Serial No. 57,804

Term of patent 3½ years

To all whom it may concern:

Be it known that I, Robert G. Peck, Jr., a citizen of the United States, residing in Chicago, Cook County, Illinois, have invented a new, original, and ornamental Design for a Container Cap or the like, of which the following is a specification, reference being had to the accompanying drawing, forming a part hereof.

I claim:—

The ornamental design for a container cap or the like substantially as shown.

ROBERT G. PECK, JR.
